UNITED STATES PATENT OFFICE.

OSBERT S. BURKE, OF CHICAGO, ILLINOIS, ASSIGNEE TO FEDERAL SIGN SYSTEM, OF NEW YORK, N. Y., A CORPORATION OF NEW YORK.

SIREN.

1,323,826.

Specification of Letters Patent.

Patented Dec. 3, 1918.

Application filed April 22, 1918. Serial No. 208,521.

To all whom it may concern:

Be it known that I, OSBERT S. BURKE, a citizen of the United States, residing at Chicago, in the county of Cook and State 5 of Illinois, have invented a certain new and useful Improvement in Sirens, of which the following is a specification.

My invention relates to sound producing devices particularly sirens, and the object 10 of the invention is to provide simple and efficient means for throwing the sound in different directions. More specifically, the horn through which the sound is emitted is mounted on a rotatable housing provided 15 with vanes in such manner that the air emerging from the air holes in the siren and impinging upon the vanes causes the housing and the horn to rotate, thus directing the sound around a complete circle.

20 I obtain my object by the mechanism illustrated in the accompanying drawings in which

Figure 1 is an elevation chiefly in central section showing the complete device.

25 Fig. 2 is a plan section taken on the line 2—2, Fig. 1.

Like numerals denote like parts throughout the several views.

In the particular form selected to illustrate the invention the motor 1 is mounted 30 in a casing 2 supported by legs 3 of any suitable type. Supported upon the casing is a base plate 4 on which is mounted the stator 5 of the siren. Within the stator 35 and above the base plate 4 is mounted the rotor 6 which is rigidly secured to the shaft 7 of the motor. The peripheral walls of the rotor and the stator are apertured in accordance with common practice, the result 40 being that when the motor drives the rotor air will be driven out through the apertures and produce sound in the well known manner.

A housing 10 which is considerably larger 45 in size than the stator is placed over the stator and is supported upon the base plate 4 through the agency of a ball bearing 11. This ball bearing serves the dual purpose of 50 rotatably supporting the housing on the base plate and holding it centered thereon. Said housing is dome shaped or approximately spherical, and at the top communicates with the horn 12 which amplifies and directs the sound. Vanes 14 are formed on 55 the inside of the housing, these being ar-

raigned vertically in the present instance, and extending not radially but somewhat obliquely to the radii, with the result that the current or blast of air emerging through the sound apertures in the stator will strike 60 said vanes and in being deflected will cause the housing to rotate. The rotation of the housing causes the horn to revolve and thus throw the sound progressively in all directions.

By preference the housing bulges outward and upward from its base, the purpose being to cause the air as it emerges from the sound apertures to move 65 dialy outward and then upon striking the 70 internal walls of the housing to be gradually deflected upward and thence inward toward the central point at the top of the housing. This not only improves the acoustic properties of the device but also renders the air 75 currents more efficient in imparting rotary movement to the housing. In other words, the air emerging from the stator sweeps first outward then gradually outward and upward, then upward and inward, finally 80 converging at the top of the housing at the point where the neck of the horn joins it.

It will be evident from the foregoing that the revolving movement of the horn is effected simply through the momentum of the 85 air which produces the sound. On account of its anti-friction bearing the housing moves very easily and the result is that the desired rotary movement of the housing and horn is obtained without involving the use 90 of any moving parts such as gearing and the like. The number and pitch of the vanes of course may be varied without departing from the spirit of the invention, and the structure may be modified in certain details 95 without destroying its utility.

Having thus described my invention what I claim as new and desire to secure by Letters Patent, is:

1. In combination, a sound producing device, a rotatable member surrounding it, vanes on said rotatable member on which the air emerging from the sound producing device impinges said vanes being placed at an angle to the air currents whereby they 100 cause the rotatable member to rotate, and sound directing means adapted to be rotated by said rotatable member.

2. In combination, a sound producing device, a rotatable housing inclosing it, said 105

housing having an opening in it for delivering the sound, and vanes fastened to said housing and arranged at an angle to the radii thereof in position to be struck by the air emerging from the sound producing device.

3. A siren having a rotor, a stator, a chambered housing inclosing the stator, said housing being rotatable, and having internal vanes adapted to be impinged by the air emerging from the rotor and stator for driving the housing, said housing having a horn communicating with the inside of it and leading away from the housing toward the side thereof.

4. A siren having a stator, a rotor within the stator, an imperforate chambered rotatable housing inclosing the rotor and stator, the space within the housing being much greater than the space occupied by the rotor and stator, and the housing being somewhat spherical in form; vanes fastened to the inner walls of the housing, said vanes being arranged at an angle to the air currents emerging from the rotor and stator, and a duct communicating with the inside of the housing and leading off toward one side thereof for amplifying and directing the sound.

5. A siren having a stator, a rotor arranged with a vertical axis and having sound apertures in the peripheral walls, a somewhat spherical housing inclosing the stator and being spaced therefrom at the sides and top, vanes secured to the inside of the housing and rising upward above the top of the stator, said vanes being arranged at an oblique angle with respect to the radii of the housing, the housing having an opening at the top and a horn leading laterally from said opening for directing the sound.

6. In combination, a siren having a rotor revoluble about a vertical axis, a motor having a shaft for supporting and revolving said rotor, a stator inclosing said rotor, the stator and rotor having sound apertures in the peripheral walls, a somewhat spherical hous-

ing placed around and over the stator and provided with internal vanes arranged non-radially, the housing having an opening at the top approximately in line with the axis of the rotor; means for supporting the housing and permitting it to rotate about a vertical axis coincident with the axis of the rotor, the housing having an opening in it for the escape of sound, and a sound duct leading from opening.

7. In combination, a siren having a rotor, a stator inclosing the rotor, the rotor having a vertical axis, supporting means for the stator, a housing inclosing the stator and rotor, an anti-friction bearing for the housing concentric with the rotor, vanes on the inside of the housing arranged non-radially for deflecting the air emerging from the rotor and stator, and thereby causing the housing to revolve, said housing having an opening in it for the emission of sound.

8. In combination, a siren having a rotor, a stator inclosing the rotor, the rotor having a vertical axis, supporting means for the stator, a housing inclosing the stator and rotor, an anti-friction bearing for the housing concentric with the rotor, vanes on the inside of the housing arranged non-radially for deflecting the air emerging from the rotor and stator, and thereby causing the housing to revolve, said housing having an opening in it for the emission of sound; said opening being located at the center of the top of the housing, and having a horn leading laterally from it for amplifying and directing the sound.

9. In combination, a revoluble megaphone, a siren having a stator and a rotor having sound holes in the sides through which air is forced by the centrifugal action of the rotor, and means adapted to be actuated by the air emerging from the sound holes for revolving said megaphone.

In witness whereof I have hereunto subscribed my name.

OSBERT S. BURKE.
